UNITED STATES PATENT OFFICE.

J MONROE ALEXANDER, OF SPANISH FORK, UTAH.

VICE.

Application filed June 1, 1927. Serial No. 195,771.

The present invention has reference to a clamp or vise especially designed to be secured to a carpenter's bench or the like, for clamping an article to the bench to permit 5 the article to be worked on with facility.

The primary object of the invention is to provide a device of this character which may be adjusted for use in connection with articles of various thicknesses, to insure the 10 article under operation being securely clamped.

A further object of the invention is to provide a clamp or vise of this character wherein the movable jaw thereof will be 15 automatically returned to its initial position when the lever is moved to its vertical position.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

Referring to the drawing:

Figure 1 is an elevational view illustrating a clamp constructed in accordance with the invention.

Figure 2 is a sectional view taken on line 2—2 of Figure 3.

Figure 3 is a plan view of the device.

Figure 4 is a sectional view taken on line 35 4—4 of Figure 3.

Referring to the drawing in detail, the device includes a plate 5 secured to the under surface of the bench or table top, to which 40 the clamp or vise is to be secured, there being provided bolts 6 extended through the plate 5 and plate 7 positioned on the upper surface of the bench or table, for securing the plates to the support.

45 The forward edge of the plate 7 is provided with a depending flange 8 designed to engage the forward edge of the bench or table top as shown by Figure 2, thereby holding the clamp against rearward movement as a board or article is being placed therein.

Extending downwardly from the plate 7 are tubular members 9 which pass through 50 openings of the supporting surface or bench top indicated at 10, the lower ends of the tubular members 9 being threaded to ac-

commodate the caps 11 which support the coiled springs 12 that in turn engage the lower ends of the rods 13 that move in the tubular members 9.

These rods 13 are carried by the upper jaw 14 of the clamp as clearly shown by Figure 4 of the drawing and act as means for guiding the upper jaw in a true vertical plane when the clamp is being operated.

Notches 15 are formed in the outer surfaces of the tubular members 9, which notches define shoulders 16, which shoulders are adapted to contact with the plate 17 which is formed with elongated openings to 70 accommodate the tubular members 9. Springs 18 are carried by the plate and engage the tubular members 9 at the sides opposite to the sides in which the notches 15 are formed, to the end that the plate is normally urged laterally to contact with the shoulders 16 falling opposite to the plate after the plate has been adjusted.

The plates 5 and 7 as well as the jaw 14 are provided with aligning openings through 80 which the rod 19 extends, the rod 19 being provided with a threaded portion 20 fitted within a threaded opening formed intermediate the ends of the plate 17 as shown by Figure 4, to the end that by rotating the 85 rod 19 an adjustment of the jaw 14 may be had.

As shown, the upper end of the rod 19 is slotted to accommodate the lever 21, which has offset portions 22, the lever being pivotally mounted within the slotted portion by means of the bolt 23. Disposed under the offset portions 22 is a contact member 24 that overlies the opening in the jaw 14 and contacts with one edge of the offset portions 22 so that when the lever 21 is moved, the enlargement will move over the member 24 to move the jaw 14 downwardly against the tension of the springs 12, the springs 12 acting to return the jaw 14 to its initial position when the lever 21 is returned to its upright or vertical position.

A bearing member 25 is secured to the rod 19 and fits within the opening of the plate 7, to hold the rod in a true vertical position and insure against binding or lateral movement of the rod when the lever is being operated.

From the foregoing it will be seen that by rotating the rod 19, the plate 17 may be 110 adjusted longitudinally of the tubular members 9, varying the space between the plate

7 and jaw 14 to adapt the device for use in connection with articles of various sizes, it being understood that the adjustment is made in such a way that the jaw will contact with the article to be clamped, so that when the lever is moved downwardly, the jaw 14 will be placed under pressure to securely clamp the article.

I claim:

1. In a clamp, a stationary jaw, tubular members extending from the stationary jaw, a movable jaw, rods connected with the movable jaw and extending into the tubular members, means for normally urging the movable jaw away from the stationary jaw, said tubular members having notches formed thereon, a plate movable over the tubular members and contacting with the notches to normally hold the plate against movement, said plate having a threaded opening, a threaded rod extending into the threaded opening, and adapted to be adjusted with

respect to the plate, and a lever carried by the rod for contacting with the movable jaw to move the movable jaw towards the stationary jaw.

2. In a clamp, a stationary jaw, means for securing the stationary jaw to a support, tubular members extending from the stationary jaw, said tubular members having notches defining shoulders, a plate having elongated openings to accommodate the tubular members, the walls of the openings adapted to cooperate with the shoulders to adjustably support the plate with respect to the tubular members, a rod adjustably connected to the plate and extending through the jaws, and a lever pivotally connected with the rod for moving the movable jaw towards the stationary jaw.

In testimony that I claim the foregoing as my own, I have hereto affixed my signature.

J MONROE ALEXANDER.
